UNITED STATES PATENT OFFICE.

CHARLES K. PICKLES, OF ST. LOUIS, MISSOURI, ASSIGNOR TO RICHARD C. POPE, OF SAME PLACE.

STREET-ROLLER.

SPECIFICATION forming part of Letters Patent No. 296,446, dated April 8, 1884.

Application filed August 16, 1883. (No model.)

To all whom it may concern:

Be it known that I, CHARLES K. PICKLES, of the city of St. Louis, in the State of Missouri, have invented a certain new and useful 5 Improvement in Rollers, of which the following is a full, clear, and exact description, reference being had to the accompanying drawings, forming part of this specification, and in which—

10 Figure 1 is a top view, and Fig. 2 an end view.

My invention relates to a roller intended more especially for use as a street-roller, but may also be used as a field-roller.

15 My invention consists in features of novelty hereinafter fully described, and pointed out in the claims.

Referring to the drawings, A represents the roller, and B the frame. The frame surrounds 20 the roller, as shown, and is supported on gudgeons A', secured to the roller. It is rectangular in shape, and its front and back strips are connected by an arch, C. The arch is securely fastened to the frame by bolts C', as shown, or 25 by other suitable means.

D D' are brackets or ears secured to the front and back strips of the frame B near their centers, being in line or nearly in line with the arch, as shown. The brackets have three sets 30 of holes, E E' E'', each, one in the center and one near each corner.

Supported by the arch, and secured thereto by a pivot-bolt, F', is a swinging beam or frame, F, the point of bearing being over the 35 center of the roller. One end of this swinging frame may be provided with a counter-balance, G, and the other end is provided with a socket or other means for the attachment of the tongue H, and also with a socket, I, to receive the brackets or ears D D'; and it has 40 holes to receive a pin, J, by which it can be made fast to either of the brackets or ears, or in either hole thereof. Now, it will be seen that when it is desired to move the roller in 45 the other direction from which it is or has been moving it does not become necessary to

turn the roller, but merely to pull out the pin J, and the team can be turned without the roller, the swinging frame turning on its pivotal center, and when the socket on the frame 50 has embraced the bracket or ear on the other side of the roller it is connected therewith by the pin J, as described.

Sometimes it is more convenient not to have the team in a direct line with or right in front 55 of the roller, (as, for instance, rolling along the side of a ditch, &c.,) and then it (the team) can be turned to one side or out of a direct line by connecting the swinging frame with one corner of the bracket or ear by placing 60 the pin J in one of the holes E or E''. (See dotted lines, Fig. 1.)

I claim as my invention—

1. In a roller, the swinging beam or frame, to which the tongue is secured, supported by 65 an arch to which it is pivoted above the center of the roller, in combination with suitable means for connecting the beam to the frame of the roller, substantially as set forth.

2. In a roller, the swinging frame or beam, 70 to which the tongue is secured, supported by an arch to which it is pivoted above the roller, in combination with the brackets secured to the frame of the roller, and having three holes each, one in the center and one in each corner, 75 and adapted to engage a socket on the swinging frame or beam, and to be connected therewith by a suitable pin, substantially as and for the purpose set forth.

3. The combination of roller A, frame B, 80 arch C, counterbalanced swinging frame or beam F, pivoted to the arch, and having means at one end for the attachment of the tongue, and a socket, I, to receive the brackets on the frame, and the brackets D D', secured to the 85 frame B, all substantially as shown and described, for the purpose set forth.

CHARLES K. PICKLES.

In presence of—

GEO. H. KNIGHT,
EDW. E. ISRAEL.
